UNITED STATES PATENT OFFICE

134,715

DESIGN FOR A HANGING MIRROR

Marie F. Smith, Berrien Center, Mich.

Application July 27, 1942, Serial No. 107,727

Term of patent 7 years

To all whom it may concern:

Be it known that I, Marie F. Smith, a citizen of the United States of America, residing at Berrien Center, in the county of Berrien and State of Michigan, have invented a new, original, and ornamental Design for a Hanging Mirror, of which the following is a specification, reference being had to the accompanying drawing, forming a part thereof.

Fig. 1 is a perspective view of the hanging mirror showing my new design.

Fig. 2 is section on the line 2—2 of Fig. 1.

Fig. 3 is a rear view of the hanging mirror.

I claim:

The ornamental design for a hanging mirror, as shown.

MARIE F. SMITH.
